DRAWER SUSPENSION

Walter E. Woodin, Rahway, N. J., assignor to
 Security Steel Equipment Corporation, Avenel,
 N. J., a corporation of New Jersey

Application October 26, 1949, Serial No. 123,604

4 Claims. (Cl. 308—3.8)

1

This invention relates to drawer suspensions and more particularly to metallic extension suspensions that permit the drawer to be withdrawn for its full depth, that is, with the drawer completely out of its case or cabinet so as to permit the rearmost contents to be lifted straight up for removal. The purpose of this invention is to provide an improved suspension of this type that has a positive progressive action and is both economical to manufacture, easy to operate, and trouble-free in its operation.

Prior attempts have been made to accomplish this but all such suspensions so far as is known, are subject to getting "out of time" if the drawer load is unbalanced or improperly used. Furthermore, such attempts have involved the use of more rollers or other equivalent mechanisms than is necessary or usual to employ in drawer suspensions in which the drawer is not fully exposed when withdrawn. The use of additional rollers or other devices not only increases the cost of the suspension but, because of the space occupied, necessitates larger drawer housings or cabinets to enclose the additional mechanism for a given drawer capacity, thus further increasing the cost.

This invention makes it possible to have a fully extended and exposed drawer without the use of additional rollers over and above those usually employed and without the necessity of enlarging the size of the drawer housing or suspension. A better understanding of this invention will be obtainable from the following description given in connection with the drawings in which:

Fig. 1 is a vertical sectional section illustrating a portion of a cabinet with two drawers, one in closed position and one in fully open position;

Fig. 2 is a transverse section through a portion of a cabinet and one drawer including the drawer suspension;

Fig. 3 is an enlarged detail of the central portion of the suspension.

Referring more particularly to the drawings, this invention is shown as applied to a drawer suspension in which the traveling neutral members are connected by cross bars to form a cradle rather than that type of suspension in which the neutral members are independent of each other although it will be obvious that this invention is applicable to either type of drawer suspension. In the following description the suspension for one side of the drawer only will be described as it will be understood that the parts are duplicated for the other side of the drawer as is necessary and customary in this type of suspension.

Upon each side of the cabinet or casing 1 and 55, with an inclined front edge or wall 30 for guiding

2

for each drawer 3 there is secured a stationary channel-shaped track or casing 5 having upper and lower horizontal rails 7 and 8 respectively. Each stationary track is fastened to the cabinet in any suitable manner such as by a projecting tongue 11 at the rear, two downwardly projecting tongues 13 at the front hooked in the end frame members and locked in position by a horizontal tongue 15 stuck out at the front end of the track.

Sliding within each track 5 is the usual traveling neutral member indicated generally by the reference character 17, it likewise being a channel-shaped member having an upper horizontal flange 18 and lower horizontal flange 19 connected by a vertical wall 20. At its rear upper end the neutral member is provided with a rear roller 21 which is mounted with its upper periphery extending just through a cutout in the upper flange 18 so as to engage the under surface of the upper rail 7 of the stationary track. At its forward end the neutral member is provided with a second or forward roller 22 which projects slightly through a cutout in the lower flange 19 in position to engage the upper surface of the lower rail 8. The neutral member is also provided with a third or intermediate roller 23 projecting through a cutout in the lower flange 19 slightly to the rear of the center thereof and in position to engage the upper surface of the lower rail 8. A fourth or propeller roller 24 is also carried by the neutral member and projects through another cutout in the lower flange 19 at a point slightly forward of the center of the neutral member and engages the upper surface of the lower rail 8. The propeller roller is mounted upon a bracket 26 pivoted at 27 to the vertical wall 29 of the neutral member and thus is capable of arcuate movement toward and from the lower rail 8 to insure contact with the rail and positive progressive movement of the cradle. This roller, as is customary in this type of suspension, is the roller which insures the forward and backward movement of the neutral member in proper timed relation to the stationary track and to the drawer track as the drawer is pulled outwardly and returned inwardly. When the drawer is in closed position the propeller roller rests in the forward inclined portion of a depression 9 formed in the lower track 8 and thus urges the drawer to closed position. The neutral member is also provided with the usual floating upper roller 28 supported within a slotted housing 29 for rolling and limited linear movement. The housing 29 is provided

the drawer track into position if it has been withdrawn for any purpose.

One of the problems inherent in an extension suspension is the proper support of the drawer track and drawer when the latter is fully withdrawn and its track is beyond the propeller roller. If the drawer weight is at the rear it is particularly necessary to support and guide the rear end of the drawer track when the drawer is completely exposed. According to this invention, the bracket 26 is extended upwardly to a point just below the top periphery of the propeller roller to provide an upper substantially horizontal edge 26' which serves to support and guide the drawer track when it is fully extended as it is when the drawer is fully exposed, or when it is being returned from fully extended position as will be described in greater detail hereafter. The forward end of the bracket also extends beyond the pivot point of the bracket and is tapered downwardly as at 31 so as to guide the drawer track into position and over the propeller roller during replacement of the drawer if it has been removed for any reason.

As is customary in this type of suspension, each drawer carries a drawer track 32 upon each side, each drawer track having a horizontal rail 33 which slides into said neutral member over the forward rollers 22, propeller rollers 24, and intermediate rollers 23, and under the floating roller 28. That is, the drawer tracks extend and travel between the floating rollers above them and the intermediate, propeller, and forward rollers of the neutral member below them.

Another of the inherent difficulties in an extension suspension is to prevent dropping or sagging of the neutral member as it reaches the limit of its forward movement upon full extension or withdrawal of the drawer. In this position the drawer track goes beyond or forward of the propeller roller and permits the latter to raise, and the neutral member correspondingly to drop unless something is done to prevent it. According to this invention, the neutral member is provided with a downwardly projecting skid or blister 35 struck outwardly from the lower flange 19 between the intermediate and propeller rollers preferably at a point adjacent the propeller roller 24 so as to engage the lower rail 8 of the stationary track as the propeller roller rises due to the absence of the overlying drawer track rail and the weight of the drawer. It has been found that if the depth of the blister is about one sixtieth of an inch less than the downward projection of the roller, no appreciable drag is noticeable upon the drawer beyond a possible tendency to hold the drawer in open position against the tendency to move upon extraction of papers from the drawer.

The neutral member is also provided with the usual back bumper 37 which engages a rear flange 38 of the stationary track and with a pivoted front bumper 39 which engages a strike 40 on the front of the cabinet to limit the forward movement of the neutral member. This latter bumper is pivotally mounted to permit it being raised to ineffective position if it is desired to remove the cradle.

It will be obvious from the foregoing that there has been provided a drawer suspension which permits full extension of the drawer and yet involves no more rollers or space occupying mechanisms than is customarily used in a standard drawer suspension, due to the use of the skid and bracket for the propeller roller, neither of which requires any enlargement of the suspension or cabinet over

and above that normally used in a drawer suspension of this type. The bracket insures against undue dropping of the drawer track and drawer when fully withdrawn should the predominating weight be at the rear of the drawer, and further guides the drawer track into position. The skid insures against undue dropping of the neutral member when the drawer track leaves the propeller roller. The drawer suspension of this invention also permits ready removal and replacement of either the drawer or cradle or both because in reinserting the drawer, the drawer tracks are guided between the inclined front ends of the propeller brackets and the floating roller housings and are easily and readily guided up to and over the propeller rollers.

It will be obvious to those skilled in the art that variations of the exact structure illustrated by way of example only, may be made without departing from the spirit and scope of this invention as defined in the appended claims.

I claim:

1. In a drawer suspension in combination, a stationary track having upper and lower rails; 25 a traveling neutral member slidably within said stationary track; and a drawer track slidable in said neutral member, said latter member having a rear roller engaging said upper rail, a forward roller engaging said lower rail and said drawer track, an intermediate roller engaging said lower rail and said drawer track, a propeller roller forward of said intermediate roller and adapted to engage said lower rail and said drawer track, said latter roller being movable toward and from said lower rail, a downwardly projecting skid positioned between said intermediate and propeller rollers and adapted to clear said lower rail when said drawer track overlies said propeller roller and engage said lower rail when said drawer track leaves said propeller roller, and a floating upper roller engaging said drawer track, said drawer track being adapted to slide between said floating upper roller and said intermediate, propeller, and forward rollers, and being adapted to travel forwardly until its rear end extends beyond the forward end of said stationary track.

2. In a drawer suspension in combination, a stationary track having upper and lower rails; a traveling neutral member slidable in said stationary member; and a drawer track slidable in said neutral member, said latter member having a rear roller engaging said upper rail, a forward roller engaging said lower rail and said drawer track, an intermediate roller engaging said lower rail and said drawer track, a propeller roller forward of said intermediate roller and adapted to engage said lower rail and said drawer track, a pivoted bracket secured to said neutral member for supporting said latter roller for movement toward and from said lower rail, said bracket extending forward of said latter roller in position to engage and support said drawer track as it leaves said propeller roller in moving forward, and a floating upper roller engaging said drawer track, said drawer track being adapted to slide between said floating upper roller and said intermediate, propeller, and forward rollers and being adapted to travel forwardly until its rear end extends beyond the forward end of said stationary track.

3. In a drawer suspension in combination, a stationary track having upper and lower rails; a traveling neutral member slidable in said stationary member; and a drawer track slidable in said neutral member, said latter member having

a rear roller engaging said upper rail, a forward roller engaging said lower rail and said drawer track, an intermediate roller engaging said lower rail and said drawer track, a propeller roller forward of said intermediate roller and adapted to engage said lower rail and said drawer track, a pivoted bracket for supporting said latter roller for movement toward and from said lower rail, said bracket extending forward of said latter roller in position to engage said drawer track as it leaves said propeller roller in moving forward, a downwardly projecting skid positioned between said intermediate and impeller rollers and adapted to engage said lower rail, and a floating upper roller engaging said drawer track, said drawer track being adapted to slide between said floating upper roller and said intermediate, propeller, and forward rollers, and being adapted to travel forwardly until its rear end extends beyond the forward end of said stationary track.

4. In a drawer suspension in combination, a stationary track having upper and lower rails; a traveling neutral member slideable in said stationary member; and a drawer track slideable in said neutral member, said latter member having a rear roller engaging said upper rail, a forward roller engaging said lower rail and said drawer track, an intermediate roller engaging said lower

5 rail and said drawer track, a propeller roller forward of said intermediate roller and adapted to engage said lower rail and said drawer track, said latter roller being movable toward and from said lower rail, a downwardly projecting skid positioned between said intermediate and propeller rollers and adapted to engage said lower rail, a floating upper roller engaging said drawer track, said drawer track being adapted to slide between said floating upper roller and said intermediate, propeller, and forward rollers and being adapted to travel forwardly until its rear end extends beyond the forward end of said stationary track, and means forward of said propeller roller for engaging and supporting the rear end of said drawer track in its most outward extended position when its rear end is forward of said propeller roller.
